DESIGN FOR A STAND FOR HOLDING COSMETICS AND SIMILAR ARTICLES

James W. Wheeler, Cincinnati, Ohio

Application September 7, 1945, Serial No. 121,920

Term of patent 14 years

(Cl. D58—26)

To all whom it may concern:

Be it known that I, James W. Wheeler, a citizen of the United States of America, residing at Cincinnati, in the county of Hamilton and State of Ohio, have invented a new, original, and ornamental Design for a Stand for Holding Cosmetics and Similar Articles, of which the following is a specification, reference being had to the accompanying drawing, forming a part thereof wherein:

I claim:

The ornamental design for a stand for holding cosmetics and similar articles, as shown.

JAMES W. WHEELER.
